CLAIM

The ornamental design for a surface configuration of a front bumper for a vehicle, as shown and described.

DESCRIPTION

FIG. 1 is a front view of a surface configuration of a front bumper for a vehicle according to my novel design;

FIG. 2 is a right perspective view thereof, the left perspective view being mirror symmetrical; and,

FIG. 3 is a right side view thereof, the left side view being mirror symmetrical.

The broken lines are for illustrative purposes only and form no part of the claimed design.
